LAMP BASE

Eli Silvestri, Pittsburgh, Pa.

Application March 19, 1953, Serial No. 24,103

Term of patent 7 years

(Cl. D48—20)

To all whom it may concern:

Be it known that I, Eli Silvestri, a citizen of the United States of America, residing at Pittsburgh, Pennsylvania, have invented a new, original, and ornamental Design for a Lamp Base, of which the following is a specification, reference being had to the accompanying drawing, forming a part hereof.

Fig. 2 is a front view thereof, and

Fig. 3 is a rear view of the structure of Fig. 1. The dominant features of my design are shown in solid lines.

I claim:

The ornamental design for a lamp base, as shown and described.

ELI SILVESTRI.
